UNITED STATES PATENT OFFICE.

EDOUARD BELIN, OF PARIS, FRANCE.

PERFORATING APPARATUS FOR TELEGRAPHIC STRIPS.

1,063,940.

Specification of Letters Patent.

Patented June 3, 1913.

Original application filed April 25, 1911, Serial No. 623,328. Divided and this application filed December 20, 1911. Serial No. 666,915.

To all whom it may concern:

Be it known that I, EDOUARD BELIN, a citizen of the Republic of France, residing at Paris, in the Republic of France, have 5 invented certain new and useful Improvements in Perforating Apparatus for Telegraphic Strips, of which the following is a specification.

This invention relates to perforating apparatus for making perforated tapes or bands for use in transmitting telegraphic messages. The apparatus is more particularly designed for use in connection with the teletype and tachytelegraph machines described in patent application, Serial No. 623,328, filed 25th April 1911, from which the present application is a division.

In most telegraphic apparatus using automatic transmission by means of a perforated 20 band or tape each letter is symbolized by a series of successive impulses and the different letters and characters are distinguished from each other by the different combinations of positive or negative, short 25 or long, signals.

In the prior application above referred to is described an apparatus which only requires for sending any character whatever the emission of a single current impulse and 30 only requires for each character a number of perforations on a straight line at right-angles to the edge of the tape and therefore only necessitates a movement of the band corresponding to the length of a single perforation after each character has been sent. It is in connection with such apparatus that the perforator which forms the subject matter of the present application was designed although the invention may be applied to 35 other forms of teletype and tachytelegraph machines.

The band is perforated either directly by the action of the keyboard of the composing machine as fast as the composition is done, 45 or by the action of a typewriting machine resembling the ordinary typewriter. It is this advantage which enables in dactylography the correction of the text represented by the perforations to be retained either on 50 the tape itself or on a detachable block or counterfoil.

In the case of a teletype machine which is required to transmit the text of newspapers and the like of a definite length, it is necessary to provide in addition to the keys for 55

the transmission of the characters special keys for "synchronism" and for "changes of alphabet." As will be seen hereinafter these perforate in a different manner from the character keys. 60

The method of construction and of operation will be described in connection with the accompanying drawings, in which:—

Figure 1 is a diagrammatic view of the perforator and the parts connected with it; 65 Fig. 2 is an elevation of one of these parts called the "electromagnet of polarity."

Each character is transmitted by means of three identical perforations distributed on the same straight line α α at right-angles to the direction in which the tape 1 is moved. 70 These three perforations are:—one for selecting the potential of the current; one for selecting a suitable resistance to be added to the line; one for selecting the direction of 75 the current.

The perforations are made by the depression of a punch 2 fixed at the end of an armature 3 of an electromagnet, which is sufficiently powerful to perforate without 80 hesitation the paper moved past it. The holes are preferably square, but this is not obligatory. The paper is drawn forward by two pressure rollers 5 and guided by a series of parallel rollers 6. It is held under 85 the line α α of the punches 2 by a very smooth plate 7. Holes 8 are formed in this plate 7 beneath each punch 2 in order to allow the latter to operate freely.

The three necessary perforations are produced simultaneously by the single depression of the corresponding key of the keyboard of the composing machine. After the whole of the perforations have been each time made, the paper advances to the extent 95 of one division.

In the perforator there are eighteen identical electromagnets A, B, C, D, E, distributed in two semicircles, so that all the extremities of the armatures where the punches are, are side by side on the same straight line α α . It is between these two half rings that the tape or band enters and emerges. 100 Each electromagnet is electrically connected with a certain number of keys a , b , c , each of which latter on being depressed closes three circuits a' , a'' , b' , b'' , c' , c'' . The eighteen electromagnets are distributed in the following way:—two for selecting the direction of the current, A; nine for selecting the 105 110

potential, B; five for selecting the additional resistances, C; one for "synchronism," D; one for changing the alphabet, E. They are all connected to the same 5 source of current F.

When the armature of one or other of the polarizing electromagnets A is lowered, its prolongation closes the fourth circuit g' , g^2 , the ultimate opening of which causes the 10 band or tape to advance. Under each longitudinal row of keys of the keyboard, a band of copper 10 is fixed and all these bands are connected in series in succession to one another. One of the ends of this series is free, the other is connected with one 15 of the poles of the local source of current F. A contact spring 9 which rises simultaneously with the key is fixed to this copper band and beneath each key. The flexible 20 extremities of three wires a' , b' , c' , each connected with their corresponding electromagnets and insulated from one another, abut beneath these contact springs. Consequently, when a key is depressed, the three 25 electromagnets selected are placed in circuit by the contact 9 connected with a common terminal, the three armatures 3 are lowered and the three holes are perforated simultaneously.

30 The end of the armature 3 of the electromagnet A for selecting the direction of the current (Fig. 2) closes, when lowered, the circuit g' , g^2 ; of another electromagnet 11, the armature of which has a pawl 12 bearing on a toothed wheel 13 fixed to the shaft of one of the drawing rollers 5. This armature is thus lowered simultaneously with the 35 key of the keyboard and the pawl 12 engages beneath a tooth on the wheel 13. When the operator ceases to depress the key, the polarity electromagnet A no longer acts and its armature 3 no longer closes the circuit g' , g^2 ; of the last named electromagnet 11, the armature of which in rising to its position 40 of repose takes with it the pawl 12. The toothed wheel 13 thus advances to the extent of one division taking with it the band of paper 1 which is then ready for another perforation. At the other end of the shaft 45 50 where the toothed wheel is placed, a small ratchet wheel is fixed, the object of which is to prevent the retrograde movement of the tape.

After a certain number of perforations, 55 500 for instance, a bell similar to that of

typewriting machines warns the compositor that he must operate the key for "synchronism." A special hole is then perforated in the tape and the work may be continued as before. Also when it is desired to change 60 the alphabet the special key is depressed and the corresponding punch makes a distinctive hole in the tape.

I declare that what I claim is:—

1. In a tape perforating machine the combination of a plurality of punches, a plurality of signaling electro-magnets in operative connection therewith, electrical tape feeding means, a source of electrical energy, a circuit including said tape and feeding 65 means and said source, and a contact in said circuit adapted to be closed by the armature of one of the signaling electro-magnets after each perforating operation.

2. In a tape perforating machine, the combination of a plurality of characters, electro-magnets, character punches operated by said electro-magnets, and having their ends arranged in a straight line at right-angles to the edge of the tape, a keyboard, character 70 keys thereon, circuits in connection with said keys and electro-magnets, so that each key closes a plurality of said circuits, two special electro-magnets, two special punches operated thereby and adapted to make perforations distinct from each other and from those of the character punches, circuits in connection with said special electro-magnets and two keys on said keyboard each adapted to close the circuit of one of said special 75 electro-magnets alone.

3. In a tape perforating machine, the combination of a plurality of signaling electro-magnets, a plurality of punches in operative connection therewith, a plurality of keys 80 each adapted to energize three of said electro-magnets, a tape feeding electro-magnet and a contact in the circuit of said tape feeding electro-magnet and adapted to be closed by the armature of one of the three electro-magnets energized upon each depression of one of said keys.

In witness whereof, I have hereunto signed my name this 7 day of November, 1911, in the presence of two subscribing witnesses. 85 90 95 100 105

EDOUARD BELIN.
